UNITED STATES PATENT OFFICE

HENRY MARTEN, OF TOLEDO, OHIO.

DOOR-FRAME FOR COOLING-ROOMS.

No. 820,657.

Specification of Letters Patent.

Patented May 15, 1906.

Application filed September 9, 1905. Serial No. 277,797.

To all whom it may concern:

Be it known that I, HENRY MARTEN, a citizen of the United States, residing at Toledo, county of Lucas, State of Ohio, have invented a certain new and useful Improvement in Door-Frames for Cooling-Rooms; and I declare the following to be a full, clear, and exact description of the invention, such as will enable others skilled in the art to which it pertains to make and use the same, reference being had to the accompanying drawings, which form a part of this specification.

This invention relates to door-frames for cooling-rooms.

It has for its object an improved frame in which the floor or sill is on a level with the floor of the interior of the cooling-room, ice-box, or refrigerator.

In the drawings, Figure 1 is a perspective showing the frame in position. Fig. 2 shows the several parts which constitute the front of the room. Fig. 3 is a perspective of the frame. Fig. 4 is a front elevation with the door-frame removed.

The front frame of the room or box is made of planking A and B, which may be in any desired number of pieces grooved and united by a tongue 1, which engages in the grooves of adjacent pieces. Behind the planks A and B, which are horizontal planks, are vertical planks 4 5 6. Through the wall thus formed is a rectangular opening with a deep rabbet extending across the top and down each side. This rabbet is formed by allowing the lining layer (the verticals 4 5 6) to extend in, inclosing an opening that is smaller through the lining layer than is the opening through the facing layer of planks. The opening through the facing-plank extends below the upper edge of the floor 16. The side planks 9 10, which stop at the upper edge of the floor 16, and the front surface 162 of the floor-plank form the vertical face of a rabbet that extends across the opening at the bottom thereof.

The dotted lines about the door-opening in Fig. 4 indicate the part covered by the frame when in position, and in this view is clearly shown the difference in elevation be-

tween the upper edge of that portion of the 50 plank A which lies below the door-space and the upper edge of the floor 16. This equals the thickness of the tread portion or facing 178 of the frame, so that when the frame is in position this facing and the floor are on a 55 level.

The front planks A reach below the upper edge of the floor 16 and engage on a subfloor 14, on which the entire structure rests. On the subfloor 14, in front of the horizontal 60 plank A, is a batten 15. In the rectangular space is placed a rectangular frame 17. The stiles 171 172 of this frame fill the vertical rabbets in front of the faces 7 9 and 8 10, the rail 173 fills the rabbet across the top of the 65 opening, and the sill 174 fills the rabbet in front of face 162 of the opening. The inner faces of the frame are flush with the inner faces which bound that part of the opening that extends through the lining-plank. The 70 facings 175 176 177 178 engage closely against the fronts of the planks A and B, and the opening through the finished wall is without obstruction, and especially is the sill entirely level with the floor of the room. 75

A door (not shown) closes the opening.

What I claim is—

1. In combination with a laminated wall provided with apertures of different size in adjacent layers, and with a floor portion arranged to be supported above the foundation-floor portion, there being an air-space therebetween, a door-frame having facing-pieces adapted to engage over the edges of the opening in the outer layer of the wall, and 80 inwardly-extending portions complementary to said facing-pieces, adapted to occupy the space intervening between the edges of the opening in the outer layer and the edges of the opening in the inner layer of the wall, and 85 to lie with their exposed surfaces flush with the edges of the opening through the inner layer of the wall, substantially as described.

2. In combination with the laminated front wall of a refrigerator-building, a floor portion 90 spaced from the foundation of the structure, a door-frame set in an opening in said wall, having facing portions adapted to engage

over the edges of said opening, and inwardly-extending portions of less depth than the thickness of the wall, the exposed faces of three of said inwardly-extending portions being arranged to lie in the same plane with the exposed edge of the opening through the inner layer of the wall, and the exposed edge of the remaining inwardly-extending portion

being in the same plane and continuous with the floor portion, substantially as described. ¹⁰

In testimony whereof I sign this specification in the presence of two witnesses.

HENRY MARTEN.
